UNITED STATES PATENT OFFICE.

BERNHARD DREYFUS, OF NEW YORK, N. Y.

DESIGN FOR A PENDANT.

SPECIFICATION forming part of Design No. 14,356, dated October 23, 1883.

Application filed August 31, 1883. Term of patent 7 years.

To all whom it may concern:

Be it known that I, BERNHARD DREYFUS, of the city, county, and State of New York, have invented and produced a new and original Design for Pendants, of which the following is a full, clear, and exact description.

Reference is to be had to the accompanying drawing, forming part of this specification, in which the figure is a face view of my newly-designed pendant.

The pendant is made from a piece of chenille or other analogous fabric, the diameter of which gradually increases from the ends toward the middle, the ends of which piece of fabric are united to form a ring, A. At its thinnest part the ring thus formed is suspended from a tuft, B, directly above the outer diameter of the ring, which tuft is provided with a loop, C. A ball, D, suspended from the tuft B or from the thin part of the ring, is held within the ring A, as shown.

I claim—

1. The herein-described design for a pendant, consisting of a ring suspended from a tuft, the thickness of the ring increasing from the tuft to a point diametrically opposite, substantially as set forth.

2. The herein-described design for a pendant, consisting of a ring suspended from a tuft and a ball suspended from the tuft and held within the ring, substantially as set forth.

3. The herein-described design for a pendant, consisting of a ring suspended from a tuft and a ball suspended from the tuft and held within the ring, the thickness of the ring increasing from the tuft to a point diametrically opposite, substantially as set forth.

BERNHARD DREYFUS.
